OIL BURNER

Willis G. Pope, Angier, N. C.

Application June 22, 1937, Serial No. 149,733

2 Claims. (Cl. 158—63)

The present invention relates to oil burners and has particular reference to devices of this character designed for use in tobacco curing.

An object of the invention is to provide an oil

burner adapted to be placed in the usual wood furnaces at present employed for tobacco curing houses without necessitating any changes or alterations in the construction of the furnace or house.

10 A further object is to provide an oil burner embodying means for preheating and vaporizing the fuel before reaching the burner.

Another object is to provide a burner of simple and practical construction, efficient and reliable 15 in operation, relatively inexpensive to manufacture and otherwise well adapted for the purposes for which the same is intended.

Other objects and advantages reside in the details of construction and operation as more fully 20 hereinafter described and claimed, reference being had to the accompanying drawing forming part hereof, wherein like numerals refer to like parts throughout, and in which:

Fig. 1 is a top plan view, and

25 Fig. 2 is a side elevational view with parts broken away and shown in section.

Referring now to the drawing in detail wherein for the purpose of illustration I have disclosed a preferred embodiment of the invention, the numeral 5 designates a fuel feed pipe leading from a suitable source of supply and connected to a union 6 from which branch pipes 7, 8 and 9 extend, the pipes 7 and 9 leading to horizontal, tubular burners 10 closed at each end. The 30 burners 10 connected to the respective pipes 9 and 11 are of similar construction and accordingly a detailed description of one will suffice for both. However one of the burners may be of reduced size to produce a relatively small amount 35 of heat under conditions where the larger burner is not necessary.

Each of the pipes 7 and 9 overlie the respective burners in spaced relation therefrom, the portion 40 of the pipes above the burners being of increased diameter as shown at 11 to receive a quantity of loose asbestos wool or similar packing 12. The enlarged end portion of the pipe 11 terminates into substantially U-form with one leg 13 positioned above the burner 10 and the other leg 14 45 inserted through one end of the burner and supported in spaced relation therein by a brace 15, the inner end of the leg 14 being closed and terminating short of the other end of the burner to provide a chamber 16 in said end of the burner.

50 55 The entire enlarged portion 11 of the fuel pipe

is filled with the loose wool packing, including the portion 14 and the burners 10 are likewise filled with the packing material 12 which surrounds the pipe 14. The pipe 14 and the upper portion of the burners 10 are perforated to form fuel discharge orifices 17, the fuel discharged from the orifices in the burners being ignited to produce the desired heat.

Beneath the burners 10 are arranged open pans or troughs 18 into which liquid fuel may be discharged from the pipe 8, the fuel in the pans being used to initially heat the burners 10 and pipes 11 to vaporize the fuel therein before lighting the burners.

The pipes 11, burners 10 and pans 18 are supported by standards 19.

Check valves 20 are arranged in the pipes 9 and 11 and a valve 21 is also provided for the feed pipe 8. In addition the pipes 9 and 11 are provided with control valves 22 having a pointer 23 20 associated with a dial 24 to indicate the position of the valve.

The pipe 8 leading to the pans 18 is provided with a swivel connection 25 to enable the swinging of the pipe to either of the pans 18, thus 25 utilizing a single pipe for the two pans.

In the operation of the device the fuel, preferably a low grade oil, is fed by gravity to the pipes 7, 8 and 9, the wool packing becoming saturated and restricting the flow of fuel through the pipes to enable the oil to become vaporized by the heat from the burners 10 before the oil reaches the orifices in the burners. The wool packing surrounding the pipe within the burner and in the chamber 16 prevents collection of any material quantity of unvaporized fuel in the burner, the chamber accommodating such surplus oil that may not quickly vaporize when the burner is first lighted, or that may condense in the burner after the latter is extinguished and providing for the consumption of the vapor produced therefrom through the orifices leading from the chamber.

The expansion of the oil and vapor produced by the heating thereof causes the vapor to be 45 discharged from the pin-hole orifices in the burner under pressure for proper combustion when ignited.

I claim:

1. An oil burner comprising a horizontal tubular burner, closed at each end and having discharge orifices in its upper portion, a fuel feed pipe inserted in one end of the burner and supported in spaced relation therein, the inner end of the feed pipe terminating in spaced relation 50 55

- from the other end of the burner, said feed pipe within the burner having perforated walls, said feed pipe including a portion outwardly of and overlying the burner for pre-heating and vaporizing oil therein and connected to a supply pipe, a loose absorbent filler in said feed pipe including its perforated portion and its portion overlying the burner and a loose absorbent filler surrounding the portion of the feed pipe within the burner and adapted to retard passage of fuel in advance of the discharge orifices in the burner to create back pressure therein and to cause the distribution of such pressure equally throughout the area of the burner for even discharge of the fuel from the several orifices.
5. An oil burner comprising a horizontal tubular burner, closed at each end and having discharge orifices in its upper portion, a fuel feed pipe inserted in one end of the burner and supported in spaced relation therein, the inner end
10. of the feed pipe terminating in spaced relation from the other end of the burner to provide a fuel collection chamber for excess oil fed to the burner, said feed pipe within the burner having perforated walls, said feed pipe including a portion outwardly of and overlying the burner for preheating and vaporizing oil therein and connected to a supply pipe, a loose absorbent filler in said feed pipe including its perforated portion and its portion overlying the burner, and a loose absorbent filler in the fuel collection chamber and surrounding the portion of the feed pipe within the burner and adapted to retard passage of fuel in advance of the discharge orifices in the burner to create back pressure therein and to cause the distribution of such pressure equally throughout the area of the burner for even discharge of the fuel from the several orifices.
15. An oil burner comprising a horizontal tubular burner, closed at each end and having discharge orifices in its upper portion, a fuel feed pipe inserted in one end of the burner and supported in spaced relation therein, the inner end

20. of the feed pipe terminating in spaced relation from the other end of the burner to provide a fuel collection chamber for excess oil fed to the burner, said feed pipe within the burner having perforated walls, said feed pipe including a portion outwardly of and overlying the burner for preheating and vaporizing oil therein and connected to a supply pipe, a loose absorbent filler in said feed pipe including its perforated portion and its portion overlying the burner, and a loose absorbent filler in the fuel collection chamber and surrounding the portion of the feed pipe within the burner and adapted to retard passage of fuel in advance of the discharge orifices in the burner to create back pressure therein and to cause the distribution of such pressure equally throughout the area of the burner for even discharge of the fuel from the several orifices.
